DESIGN FOR A COMBINED WORK BENCH AND CABINET OR SIMILAR ARTICLE

William A. Kent, Detroit, Mich., assignor to Hinckley-Myers Company, Jackson, Mich.

Application July 29, 1940, Serial No. 94,001

Term of patent 3½ years

To all whom it may concern:

Be it known that I, William A. Kent, a citizen of the United States, residing at Detroit, in the county of Wayne and State of Michigan, have invented a new, original, and ornamental Design for a Combined Work Bench and Cabinet or Similar Article, of which the following is a specification, reference being had to the accompanying drawing, forming part thereof.

In the drawing:

work bench and cabinet or similar article, showing my new design,

Fig. 2 is a top plan view thereof.

The printed matter shown in dotted lines is for illustrative purposes only.

I claim:

The ornamental design for a combined work bench and cabinet or similar article, substantially as shown and described.

WILLIAM A. KENT.
